(57) **CLAIM**

The ornamental design for a flip cap package with label, as shown and described.

DESCRIPTION

FIG. 1 is a top, front perspective view of a flip cap package with label according to the present design.

FIG. 2 is a bottom, right side perspective view thereof.

FIG. 3 is a front elevation view thereof.

FIG. 4 is a rear elevation view thereof.

FIG. 5 is a right side elevation view thereof.

FIG. 6 is a left side elevation view thereof.

FIG. 7 is a top plan view thereof.

FIG. 8 is a bottom plan view thereof.

FIG. 9 is a front elevation view of a second embodiment of a flip cap package with label showing the score lines on the label in solid lines.

FIG. 10 is a front elevation view of a third embodiment of a flip cap package with label with an alternate shape of the label.

FIG. 11 is a front elevation view of a third embodiment of a flip cap package with label with a further alternate shape of the label.

FIG. 12 is a front elevation view of a fifth embodiment of a flip cap package with label with yet another alternate shape of the label.

FIG. 13 is a front elevation view of a sixth embodiment of a flip cap package with label with an alternate arrangement of score lines on a label shown in solid lines.

FIG. 14 is a rear elevation view of a seventh embodiment of a flip cap package with label showing the same portions of the package as the first embodiment except for the hinge in broken lines.

FIG. 15 is a right side elevation view thereof; and,

FIG. 16 is a left side elevation view thereof.

The broken lines shown represent portions of the claim that form no part of the claimed design.
